AUTOMOBILE FLOOR MAT

Jack J. Friedman, Cleveland Heights, Ohio, assignor to
Anchor Rubber Products Inc., Cleveland, Ohio, a cor-
poration of Ohio

Application October 20, 1955, Serial No. 38,468

Term of patent 14 years

(Cl. D9—6)

Fig. 1

Fig. 2

Fig. 3

Fig. 1 is a top plan view of an automobile floor mat embodying the design of my invention.

Fig. 2 is an enlarged fragmentary plan view of a portion of the mat shown in Fig. 1, showing certain details of the design.

Fig. 3 is an enlarged fragmentary plan view of another portion of the mat shown in Fig. 1.

Fig. 4 is a cross-sectional view taken as indicated on line 4—4 of Figs. 1 or 2.

Figs. 5 is a cross-sectional view taken as indicated on line 5—5 of Figs. 1 or 3.

Fig. 6 is a cross-sectional view taken as indicated on line 6—6 of Fig. 1.

I claim:

The ornamental design for an automobile floor mat, substantially as shown.
